TRANSLATING SYSTEM

Walter S. Lemmon, New York, N. Y., assignor to
 International Business Machines Corporation,
 New York, N. Y., a corporation of New York

Application September 8, 1934, Serial No. 743,208

6 Claims. (Cl. 178—17)

This invention relates to translating systems and more particularly to systems operable under the control of indicia storing means to selectively operate the mechanism embodied in the system.

The present invention is adapted particularly to translating systems to provide automatic controlling means which in part is in the nature of a tape, sheet, or ribbon on which characters or other indicia to be reproduced are represented by perforations to selectively operate the particular associated translating mechanism.

The perforations are formed by any suitable means and are provided on a tape or sheet wide enough to contain a longitudinal series of perforations for the control of each element of the machine to be operated and used in connection with the translating procedure.

A sensing device is provided to cooperate with the perforated sheet in such a manner that when a particular perforation is sensed, a circuit corresponding to the represented indicia is energized to further control the particular associated translating mechanism.

The present invention is particularly adapted for remote control of the translating devices which may be teletypewriting devices, punches, accounting and calculating machines, facsimile devices and the like and which are controlled by some form of indicia representations.

Therefore this invention will be explained in conjunction with one particular type of mechanism adaptable to be controlled by indicia representations. It is obvious that the invention to be disclosed then is not limited to the embodied mechanism in the system and that the presented form is merely for illustrative purposes of the system.

The particular form of translating system explained in conjunction with the controlling means to be disclosed is a printing telegraph system operable by a line or radio network. This system involves the shifting of the character impulse along the axis of a timed scale, the position of the impulse thereon determining the character to be selected; and is of the type disclosed in U. S. Patent 1,927,077 issued to G. W. Watson, September 19, 1933.

It is therefore an object of this invention to provide controlling means rendered operable by a character storing device, such as a perforated sheet or strip bearing character representations and to further control the associated character recording means to cause a record to be made of

a character corresponding to a particular character representation on the storing device.

Another object of the present invention is the provision for operating the character storing device in synchronism with the character recording means to enable the translating system to be operated at the maximum transmission speed.

Another object of the present invention is the provision of an improved sensing device cooperating with the character storing means.

Further and other objects and advantages will be hereinafter set forth in the accompanying specification and claims, and shown in the drawings, which by way of illustration show what is now considered to be the preferred embodiment of the invention.

In the drawings:

Fig. 1 is a front elevational view of the sensing device.

Fig. 2 is a sectional view on line 2—2 of Fig. 1. 20
 Fig. 3 is a side view of the sensing device.

Figs. 4 and 4A show schematically systems by means of which the invention may be carried out.

Referring now to the drawings in which similar parts are designated by the same numerals in the several views, it is believed that a clear understanding of the invention will be had therefrom when considered in conjunction with the following description.

For the sake of clarifying the following description a brief explanation of the operation of the form of printing telegraph systems embodied herein will be given first, followed by a disclosure of the operation of the complete translating system, and then later followed by a detailed description of the parts of the system necessary for a full understanding of this invention.

Referring now to Fig. 4, a brief description of the operation of the printing telegraph system disclosed in the aforesaid Watson patent will be given. In the figure B represents a printing telegraph unit which may be of any well known type having a series of character pivoted key bars 10 and is adapted to initiate a character impulse when the character key is depressed. A 45 separate contact 11 is associated with each individual key bar 10 and connected to contacts or segments 12 corresponding to the character represented by each key bar.

Rotary arm 13 driven by any suitable means 50 is adapted to engage the contacts 12 in rather rapid succession to initiate the character pulse by discharging the condenser 14 coating with the transmitting commutator 15. An individual condenser is provided for each character key 55

bar 10, and is charged by depressing the key 10 to close the charging circuit through contact 16 associated with the key bar 10, battery 17, condenser 14, and key bar 10. The condenser is discharged during a predetermined interval of time when the rotary arm engages the particular character segment 12 through the circuit closed by contact 11 and fully described in the aforesaid patent. Provision is made for depressing the key bar 10 by the energization of an attached solenoid 18.

It must be understood that transmitting units of the type just explained are characterized by the provision that the different characters to be transmitted and received are represented by single impulse signals which are definitely allocated during particular timed intervals.

The character impulse as produced by the printer transmitter units B and C in the manner as just explained, is then conducted to the radio or line wave transmitter D to effect transmission of the signal impulse in a manner that is well known and need not be further explained, and is received in the usual manner by the wave receiver unit E. The received impulse is then passed to the receiving commutator or distributor F and the printing telegraph receiver unit in a manner fully disclosed in the aforesaid patent to record the character corresponding to the character transmitted. It is to be understood that the rotary arm 19 of distributor 20 is rotated by suitable means in synchronism with the rotating arm 13 of distributor 15 which is disclosed in the said mentioned patent.

It is well known how the synchronous distributors are used in the art and applied to this type of system to effect the correct selection of the type bar 21 which is depressed by energization of attached solenoid 22, and each character solenoid 40 which in turn is connected to the distributor segments or contacts 23, and therefore needs no further explanation.

Operation

In Figure 4 A represents the sensing device and translating system controlling means which will be explained in detail hereinafter. A plurality of sensing brushes 25 are positioned so as to enable them to cooperate with feed roller 26 which is adapted to introduce a perforated roll or sheet 27 between the brushes 25 and feed roll 26. The individual brushes 25 are each connected to a separate solenoid 18 so as to be able to energize the said solenoid when the corresponding sensing brush is permitted to engage the said feed roller 26 by virtue of a character perforation in the character storing means. The circuit is completed when a perforation is sensed as follows: from grounded battery 28 current is conducted to solenoid 18, the corresponding sensing brush 25, feed roller 26 which is adapted to be a conductor and grounded as indicated by line 29. When no perforation is sensed the said roll or sheet prevents the brushes from completing the solenoid circuits to energize the circuits.

The device as shown at A is provided with a horizontal transverse roller 26 which supports and feeds the elongated perforated paper sheet 27, this sheet being wide enough to contain a longitudinal series of perforations for the control of each character representation.

Therefore when the sheet is fed continuously

to the sensing device by suitable means, such as motor 30, and when the particular brush 25 senses the corresponding character perforation, the solenoid 18 is energized as previously explained to depress key bar 10 to record the character corresponding to the character perforation sensed by the said brush 25.

Upon depression of key bar 10 and upon engagement of the corresponding segment 12 by rotary arm 13, a character signal is transmitted over the net work to be received and recorded at the receiving printer unit G, in a manner as explained hereinbefore.

In this manner a plurality of recording units may be automatically controlled by a prepared character storing sheet to record the characters corresponding to the prepunched character representations.

It has been found, however, in order to obtain the maximum transmission speed from a like system that it is necessary to feed the record sheet 27 in synchronism with the recording mechanism. A preferred method for accomplishing this synchronism will be explained as follows.

Referring to Fig. 4A, the rotary arm 31 of the transmitting distributor 32 is attached to shaft 33 of motor 34 and is adapted to rotate arm 31 at a predetermined speed to cause arm 31 to engage the distributor contacts 35 in succession. An extension of the said motor shaft coacts with a speed reduction unit 36 to drive feed roller shaft 37 to rotate the feed roller at a definite speed, so that during a single complete rotation of arm 31 the speed of the feed roller is such that the perforated sheet is fed a distance equal to the distance spacing the longitudinal series of perforations, or that distance as indicated between the center lines 38 of perforations 39.

By synchronizing the sheet feed roller and transmitting distributor in this manner, it is seen that there is no loss of transmission time because of improper spacing between the character perforations, that is by spacing the perforations too far apart on the elongated sheet. From the above explanation, therefore, it is obvious that upon sensing a character perforation, a character impulse corresponding to the said perforation is transmitted by the printer transmitting units B and C in Fig. 4A before the following perforation is sensed by the brushes. It is understood how the impulse is transmitted from the transmitter unit D to the receiving printer unit and recorded by the printer from the previous explanation, and therefore further disclosure of its operation is not necessary.

Sensing device

Referring now to Figs. 1, 2 and 3, the device is shown as provided with a horizontal transverse feed roller 26, which supports and feeds an elongated perforated paper sheet 27, this sheet being wide enough to contain a longitudinal series of perforations for the control of each key lever of the transmitting or registering unit. The roller 26 is provided, at its ends, with feed pins 40, which engage marginal perforations in the paper sheet, to maintain correct registration of the paper. The roller is driven constantly in the direction of the arrow in Fig. 2 by any suitable means, one form as shown by the motor 30 directly connected to the shaft 41 to which the roller 26 is rigidly attached. The shaft 41 supporting the feed roller is mounted on end supports 42 which are fixed to the base 43. It is to be noted that the support 42 on one end as

shown in Fig. 3 is proportioned with respect to the roller 26 so that segments of the roller protrude on both sides of the support.

It was explained hereinbefore that the sheet

- 5 27 when fed by roller 26 separates the roller 26, which is a conducting element, from the sensing brushes 25 which in normal operating position as shown in Fig. 2 are adapted to engage the roller when a perforation in the sheet 27 is sensed 10 as shown in Fig. 1 to control the corresponding circuit. Sensing brushes 25 are shown mounted in a transverse insulating strip 44 which is attached to supporting end brackets 45 and are pivotally mounted on the shaft 46 supported by end plates 47. At one end as shown in Fig. 3, plate 47 is fastened to a base 44—A which is so arranged so that the plate 47 and its base 44 and support 42 and its base 43 have a gap wide enough so as to permit ingress and egress of 15 the paper sheet to the device.

Attached to brackets 45 are arms 48 circumferentially arranged around roller 26 and supporting rotatable sheet followers 49 which are adapted to hold the rotating sheet in proper position during its motion. An extension 50 of the bracket 45 is shown and adapted when the brush sensing head is in a raised position, as indicated in Fig. 2, to act as a guide for the sheets when removed or replaced in the device. The brush sensing head which is locked in its normal operating position by lock pin 51, may be released by operation of pin 51 so as to permit the raising of the sensing head.

While there has been shown and described and 35 pointed out the fundamental novel features of the invention as applied to a single modification it will be understood that various omissions and substitutions and changes in the form and details of the device illustrated and in its operation 40 may be made by those skilled in the art without departing from the spirit of the invention. It is the intention, therefore, to be limited only as indicated by the scope of the following claims.

What is claimed is:

- 45 1. In a translating system, the combination of a continuously fed character storing means, means adapted to transmit character impulses having similar characteristics during a predetermined timed interval, the time of transmission 50 therein representing the particular characters, means to control the operation of said transmitting means in accordance with the character representations of said storing means, and means included in said transmitting means to initiate 55 character impulses corresponding to the said character representations.

2. In a translating system, the combination of a continuously fed perforated sheet bearing character representations, means adapted to 60 transmit character impulses having similar characteristics during a predetermined timed interval, the time of transmission therein representing the particular characters, a plurality of circuits, means to energize a particular circuit of said 65 plurality of circuits according to the location of a perforation on said sheet, and means controlled by said energized circuit to operate said trans-

mitting means, and means included in said transmitting means to initiate a character impulse corresponding to the character represented on said sheet.

3. In a translating system, means to transmit character impulses having similar characteristics during a predetermined timed interval, the time of transmission therein representing the particular characters, means to receive said character impulses, a perforated sheet with character representations, rotary feeding means, means to set in motion said feeding means which supports and feeds said sheet continuously, sensing means associated with said sheet while in motion to control said transmitting and receiving means to transmit and receive the characters corresponding to said character representations on the said sheet.

4. In a translating system, means including rotary distributor means to transmit character impulses having similar characteristics during a predetermined timed interval, the time of transmission therein representing the particular characters, a perforated sheet with character representations, rotary feeding means, means to set 25 said feeding means in motion which supports and feeds said sheet continuously so as to operate in synchronism with said distributor, sensing means associated with said sheet while in motion to control said transmitting means to transmit 30 the characters corresponding to said character representations on the said sheet.

5. In a translating system, means including rotary contact means to transmit character impulses during a predetermined timed interval, 35 the time of transmission therein representing the particular characters, a controlling sheet with a plurality of perforations thereon representing characters, rotary feeding means for said sheet, means to operate said feeding means to feed the 40 said sheet a distance equal to the longitudinal spacing between said perforations during the timed interval the said contact means rotate one complete revolution, sensing means associated with said sheet while in motion to control said 45 transmitting means to transmit the characters corresponding to said character perforations on the said sheet.

6. In a translating system, a translating device including a continuously fed sheet with a plurality 50 of perforations thereon, representing characters, the location of the said perforations on said sheet determining the characters represented, means adapted to transmit character impulses having similar characteristics during a prede- 55 termined timed interval, the time of transmission therein representing the particular characters, means included in said translating device and associated with said perforated sheet to transform the said character perforations to electrical impulses, means controlled by the said electrical impulses to selectively control the operation of said transmitting means to transmit character impulses corresponding to the said character perforations.

WALTER S. LEMMON.
